CLAIM

The ornamental design for a theft deterrent apparatus, as shown and described.

DESCRIPTION

FIG. 1 is a top perspective view of a theft deterrent apparatus in an engaged state having a symmetrical composition;

FIG. 2 is a perspective view from the top of the apparatus in an unengaged state;

FIG. 3 is a bottom plan view of the upper portion of the apparatus in an unengaged state;

FIG. 4 is a top perspective view of the bottom portion of the apparatus in an unengaged state;

FIG. 5 is a left side plan view of the apparatus in an engaged state;

FIG. 6 is a right side plan view of the apparatus in an engaged state;

FIG. 7 is a top plan view of the upper portion of the apparatus in an engaged state; and,

FIG. 8 is a bottom plan view of the bottom portion of the apparatus in an engaged state;

The top and bottom portions have been shown separately in FIGS. 3 and 4 for convenience of illustration.

In the drawings, the broken line showing of a indicia in FIG. 8 depicts environmental subject matter and forms no part of the claim.
